UNITED STATES PATENT OFFICE.

ARTHUR O. HUBBARD, OF MINNEAPOLIS, MINNESOTA, ASSIGNOR TO PUFFER-HUBBARD MFG. CO., OF MINNEAPOLIS, MINNESOTA.

FOLDING CRATE.

1,113,636.

Specification of Letters Patent.

Patented Oct. 13, 1914.

Application filed August 16, 1909. Serial No. 513,184.

To all whom it may concern:

Be it known that I, ARTHUR O. HUBBARD, of Minneapolis, Hennepin county, Minnesota, have invented certain new and useful 5 Improvements in Folding Crates, of which the following is a specification.

The object of my invention is to provide a crate or box that is capable of being folded compactly for convenience in ship-10 ping.

A further object is to simplify the hinges, by means of which the panels of the box are united.

Other objects of the invention will appear 15 from the following detailed description.

My invention consists generally in various constructions and combinations, all as hereinafter described and particularly pointed out in the claim.

20 In the accompanying drawings, forming part of this specification, Figure 1 is a perspective view of a crate, embodying my invention, Fig. 2 is an edge view of the crate in its folded position, Fig. 3 is a horizontal, 25 sectional view, showing the construction and arrangement of the hinges, Fig. 4 is a transverse, sectional view, illustrating the manner of pivoting the bottom in the crate, Fig. 5 is a sectional view on the line $x-x$ of 30 Fig. 3, Fig. 6 is a perspective view, showing the application of the hinges of Fig. 1 to a box having closed walls, Fig. 7 is a perspective view, showing a cover for the box with an improved locking device, Fig. 8 35 is a detail view of one of the hinges for the cover.

In the drawing, 2 and 3 represent respectively the end and side panels of the crate, composed preferably of top and bottom rails 40 4, 5, 6 and 7, between which vertically arranged slats 8 are provided having their ends fitting within rabbets 9 formed on the inner edges of the top and bottom rails of the panels and secured thereto by staples 45 10.

Instead of spacing these slats apart to form a crate, they may be arranged close together to form a box and the slats may be made of varying width, according to the material at hand. At diagonally opposite 50 site corners of the crate and forming a continuation of the end panels, I provide upright posts 11, fitting within rabbets 12 in the top and bottom rails of the side panels and secured thereto and contacting when the 55 box is opened with the rounded ends 13 of

the rails 4 and 5 of the end panels and attached to these rails by means of metal brackets 14, which are secured to the posts and are pivotally connected with the rails 4 and 5 by pivot pins 15. These brackets, 60 when the crate is folded, cause the panels to be held apart in parallel relation with one another a sufficient distance to receive the bottom 16, which is hinged at 17 to one of the side panels and is adapted to be swung 65 to a vertical position when the crate is folded. The brackets 14 are arranged at diagonally opposite corners of the box and at the other corners the top rails at the sides and ends have beveled meeting faces 18 70 and shoulders and notches 19 and 20, which interlock when the crate is opened and form a close joint and brace and strengthen the corners of the box. The lower rails have beveled meeting faces 21. At the corners 75 of the crate provided with these interlocking beveled faces, I provide a form of hinge, which I regard as the essential feature of my present invention, on account of its simplicity, ease of application and durability. 80

Each hinge consists of a wire loop portion 22 having its ends clenched in one of the rails and provided with an eye 23 that is adapted to receive a hook 24 that is formed on the end of the other hinge section 25 that 85 is clenched in a corresponding manner in the abutting rail. The eye portion of the hinge section 22 is bent slightly out of the plane of the rest of the section to permit the unobstructed movement of the abutting 90 ends of the rails, allowing them to swing into alignment with one another when the crate is closed or folded and assume a position at right angles to one another when the joint is closed between them when the 95 crate is open. These hinges are made of suitable gage of wire and for a crate of this kind, will form a substantial, durable connecting means for the end and side panels.

In Fig. 6, I have shown a box 26 having closed side walls and hinges similar to those described in Fig. 1 and also strap hinges 27 particularly adapted for a box of this type.

In Fig. 7 I have shown a cover 29, having 100 hinges consisting of straps 30 and a loop 31 connecting them, secured respectively to cross bars 32 on the cover and to the upper rail 33 of the box. A locking device is provided on this cover, consisting of a loop 34, carried by a strap 35 and adapted to enter 105 110

a recess 36 in a clip 37 that is secured to the side wall of the box. This recess has a narrow throat 38 and an enlarged rear portion, so that some pressure will be required 5 to force the loop through the throat and prevent it from becoming accidentally separated from the recess. The rear of the recess is sufficiently large to allow the loop to move freely therein and at the same time, 10 hold the cover securely in its closed position. This form of lock is extremely simple and inexpensive to manufacture, can be easily and quickly attached to the box, without adding materially to the expense of manufacture. 15

I claim as my invention:—

A folding crate comprising side and end panels, each panel having top and bottom rails, posts provided at the two diagonally 20 opposite corners and in the plane of said

end panels and secured to the rails of said side panels, angle plates secured to said posts in the angles formed by the intersection of said posts and the top and bottom rails of the end panels and pivotally connected with said top and bottom rails, hinges provided at the other diagonally opposite corners of the crate, a bottom hinged to one of said side panels and adapted to swing to a vertical position between the 25 panels and into the space formed by said posts and brackets between the end and side panels, substantially as described. 30

In witness whereof, I have hereunto set my hand this 9th day of July, 1909.

ARTHUR O. HUBBARD.
